(57) **CLAIM**

What is claimed is the ornamental design for a handheld motorized facial brush having pivoting floating head with charging stand, as shown.

DESCRIPTION

FIG. 1 is an exploded right perspective view of a handheld motorized facial brush having pivoting floating head with charging stand;

FIG. 2 is a left perspective view thereof;

FIG. 3 is a left perspective view thereof, in which the brush head is underside up;

FIG. 4 is a front view of the facial brush of FIG. 1, resting in the charging stand;

FIG. 5 is a right perspective view thereof;

FIG. 6 is a right side view thereof;

FIG. 7 is a left side view thereof;

FIG. 8 is a right rear perspective view thereof;

FIG. 9 is a left rear perspective view thereof;

FIG. 10 is a front view of the facial brush of FIG. 1;

FIG. 11 is a right perspective view thereof;

FIG. 12 is a right side view thereof;

FIG. 13 is a left side view thereof;

FIG. 14 is a top view thereof;

FIG. 15 is a bottom view thereof;

FIG. 16 is a right perspective view of the facial brush of FIG. 1, shown with the brush head removed;

FIG. 17 is a left perspective view thereof;

FIG. 18 is a left side view thereof;

FIG. 19 is a right side view thereof;

FIG. 20 is a top view thereof; and,

FIG. 21 is a bottom view thereof.
